INVENTOR

UNITED STATES PATENT OFFICE.

ALBERT L. VENCILL, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING APPARATUS.

Application filed October 7, 1925. Serial No. 60,979.

My invention relates to railway signaling apparatus, and particularly to apparatus of the type comprising light signals controlled by levers in an interlocking machine.

5 I will describe two forms of signaling apparatus embodying my invention, and will then point out the novel features thereof in claims.

In the accompanying drawing, Fig. 1 is a 10 diagrammatic view showing one form of signaling apparatus embodying my invention. Figs. 2 and 3 are views similar to Fig. 1 but showing the controlling lever in different positions. Fig. 4 is diagrammatic view showing 15 a modification of the signaling apparatus shown in Fig. 1.

Similar reference characters refer to similar parts in each of the views.

Referring first to Fig. 1, the reference character S designates a railway signal comprising a proceed lamp L^G and a stop lamp L^R , both of which lamps in the form here shown are of the incandescent electric type. A beam of light is projected from the lamp L^G by 25 means of an optical device, such as a lens 2^G , whereas a beam of light is projected from the lamp L^R by an optical device, such as a lens 2^R . Usually the lenses 2^G and 2^R will be 30 distinctively colored, so that the beams projected from the two lamps will be distinguished by their colors.

The supply of operating current to the lamps L^G and L^R is controlled by a lever A, which is usually one of a plurality of similar levers comprised in an interlocking machine. This lever, in the form here shown, is a bar mounted to slide longitudinally and provided with a plurality of contact members 3, 4 and 5 arranged for co-operation respectively with fixed contact members 3^a , 4^a and 5^a . The lever A is provided with a handle 6, and also with a lock C comprising a dog 7 fixed to the lever and a latch 8 co-operating with said dog. The latch 8 may be lifted out 45 of the path of the dog 7 by a magnet 10 provided with an armature 9 which is attached to the latch 8.

The lever A has a normal position, a reverse position, and an indication position between the normal and reverse positions. As shown in Fig. 1, the lever is in its normal position, wherein the stop lamp L^R is lighted,

the circuit for this lamp being from the secondary 12 of a transformer T, through wire 20, lamp L^R , primary 26 of a transformer B, 55 wire 21, contact $4-4^a$, and wire 22 to the secondary 12 of transformer T. The primary 11 of transformer T is constantly supplied with alternating current from a source which is not shown in the drawing. 60

The lever A may be moved to the right from the position shown in Fig. 1 without interference by the lock C, because of the inclined right-hand face of the dog 7. As shown in Fig. 2, the lever has been shifted 65 to the right until it occupies its reverse position, wherein the circuit for the stop lamp L^R is open at contact $4-4^a$, and the circuit for the proceed lamp L^G is closed at contact 70 $3-3^a$, the latter circuit being from the transformer secondary 12, through wire 17, lamp L^G , wire 18, contact $3-3^a$, wire 19, to secondary 12. When the lever is in its reverse position, the proceed lamp L^G is lighted and the stop lamp L^R is extinguished. 75

The return movement of the lever A to its normal position is limited by the lock C, which permits the lever to be moved only to its indication position until this lock is released. In Fig. 3 the lever A is shown in 80 its indication position, from which view it will be seen that lamp L^G is extinguished and the circuit for lamp L^R is again closed at contact $4-4^a$. For reasons which are well understood in railway signaling practice, it is 85 important that movement of the lever A from its indication position to its normal position should be prevented until the stop lamp L^R is actually lighted. In other words, it is important that magnet 10 should be energized to release the lock C if and only if 90 lamp L^R is actually lighted. The magnet 10 is controlled by a relay R having a rotor 13 and two stator windings 14 and 15. Winding 14 is connected with the secondary 95 27 of the transformer B, so that this winding is energized if and only if operating current is actually being supplied to the circuit for lamp L^R . Winding 15 is connected across 27 the terminals of the lamp L^R , so that this 100 winding is supplied with current if and only if a difference of potential exists across the terminals of lamp L^R . If the filament of lamp L^R becomes short-circuited, there will

- be substantially no difference of potential across the terminals of the lamp and so the winding 15 will not be supplied with current. The relay R is so adjusted and connected that its contact 16 will be closed if and only if current is flowing in the lamp L^R and the proper operating voltage exists across the terminals of the lamp. If relay R is properly energized when the lever A is 10 in its indication position, magnet 10 will be energized by a circuit which passes from secondary 12 of transformer T, through wire 23, contact 16 of relay R, wire 24, magnet 10, contact 5-5^a and wire 25 to the transformer secondary 12. Magnet 10 then raises the latch 8 out of the path of dog 7, so that the lever A may be returned to its normal position. Just before the lever reaches its normal position contact 5-5^a opens, thereby 20 preventing unnecessary continued energization of the magnet 10.
- Referring now to Fig. 4, the apparatus shown herein is the same as that shown in Fig. 1, except that the relay which controls the releasing magnet 10, and which is here designated R^a, is provided with a third stator winding 28, which winding is connected with the secondary 29 of a transformer B^G. The primary 30 of transformer B^G is 30 included in the operating circuit for the proceed lamp L^G . The windings 28 and 14 are so connected as to oppose each other, that is, they are so connected that if operating current is simultaneously supplied to lamps L^R and L^G , the windings 28 and 14 will tend to 35 create torques in opposite directions in the rotor 13, and so will prevent contact 16 from closing. It follows that with the structure shown in Fig. 4, if the two lamps L^G and L^R should accidentally receive operating current simultaneously, the lock C will not be released and the lever A cannot be restored from its indication position to its normal position.
- Although I have herein shown and described only two forms of railway signaling apparatus embodying my invention, it is understood that various changes and modifications may be made therein within the 45 scope of the appended claims without departing from the spirit and scope of my invention.
- Having thus described my invention, what I claim is:
1. In combination, a signal comprising an electric lamp, means for supplying current to said lamp, and indication means for said lamp controlled jointly by the current flowing in the lamp and by the voltage across the 55 terminals of the lamp.
2. In combination, a signal comprising an electric lamp, means for supplying current to said lamp, indicating means for said lamp, and means for operating said indicating means if and only if sufficient current is 60 flowing in the lamp to light the lamp and a sufficient difference of potential exists across the lamp terminals to light the lamp.
3. In combination, a signal comprising an electric lamp, means for supplying current to said lamp, indicating means, and means for operating said indicating means if and only if sufficient current is flowing in the lamp to light the lamp and the lamp filament is intact. 75
4. In combination, a signal comprising an electric lamp, means for supplying current to said lamp, a relay having one winding in series with said lamp and a second winding connected across the terminals of the lamp, and an indication device controlled by said relay. 80
5. In combination, a signal comprising an incandescent electric lamp, a circuit for said lamp including a source of current, a relay having one winding supplied with current in accordance with the operating current flowing in said lamp circuit and a second winding supplied with current in accordance with the difference of potential across the terminals of said lamp, and an indication device controlled by said relay. 85
6. In combination, a signal comprising an electric lamp, means for supplying current to said lamp, a relay controlled by the current supplied to said lamp and by the voltage across the terminals of the lamp, and an indicating device controlled by said relay. 90
7. In combination, a signal comprising an electric lamp, means including an interlocking machine lever for controlling the supply of operating current to said lamp, a lock for limiting the movement of said lever, and means controlled jointly by the current flowing in said lamp and by the voltage across the terminals of the lamp for releasing said lock. 100
8. In combination, a signal comprising an electric lamp, an interlocking machine lever having a normal position and an indication position in both of which said lamp is lighted and a reverse position in which said lamp is extinguished, a lock for preventing movement of said lever from indication position to normal position, and means controlled jointly by the current flowing in said lamp and by the voltage across the terminals of the lamp for releasing said lock. 110
9. In combination, an interlocking machine lever having normal, reverse and indication positions; a signal comprising a stop electric lamp and a proceed electric lamp; means controlled by said lever for supplying operating current to said stop lamp when the lever is in the reverse position and in the indication position, and for supplying operating current to said proceed lamp when the lever is in its reverse position; a lock for preventing movement of said lever from its indication position to 120
- 65 125 130

its normal position; means controlled jointly by the current flowing in said stop lamp and by the voltage across the terminals of said stop lamp for releasing said lock, and 5 means for preventing release of said lock if current is being supplied to said proceed lamp.

10. In combination, an interlocking machine lever having normal, reverse and indication positions; a signal comprising a stop electric lamp and a proceed electric lamp; means controlled by said lever for supplying operating current to said stop lamp when the lever is in the reverse position and in the indication position, and for 15 supplying operating current to said proceed lamp when the lever is in its reverse position; a lock for preventing movement of said lever from its indication position to 20 its normal position; a relay having a first winding supplied with current in accordance with the operating current flowing in the stop lamp, a second winding supplied with current in accordance with the voltage 25 across the terminals of the stop lamp, and a third winding supplied with current in accordance with the operating current flowing in said proceed lamp; and means controlled by said relay for releasing said lock.
- 30 11. In combination, a signal comprising an electric lamp, means including an interlocking machine lever for controlling the supply of operating current to said lamp, a lock for limiting the movement of said lever, and means for releasing said lock if and only if sufficient current is flowing in 35

said lamp to light the lamp and a sufficient difference of potential exists across the lamp terminals to light the lamp.

12. In combination, a signal comprising 40 an electric lamp, means including an interlocking machine lever for controlling the supply of operating current to said lamp, a lock for limiting the movement of said lever, and means for releasing said lock if 45 and only if sufficient current is flowing in the lamp to light the lamp and the lamp filament is intact.

13. In combination, a signal comprising 50 an electric lamp, means including an interlocking machine lever for controlling the supply of operating current to said lamp, a lock for limiting the movement of said lever, a relay having one winding supplied with current in accordance with the operating current flowing in said lamp and a second winding supplied with current in accordance with the difference of potential 55 across the terminals of said lamp, and means controlled by said relay for releasing said lock.

14. In combination, a signal comprising 60 an electric lamp, means including an interlocking machine lever for controlling the supply of operating current to said lamp, a lock for limiting the movement of said lever, and means controlled in part by the voltage across the terminals of said lamp for releasing said lock.

In testimony whereof I affix my signature.

ALBERT L. VENCILL.
